UNITED STATES PATENT OFFICE.

FREDERICK MACKINTOSH, OF SCHENECTADY, NEW YORK, ASSIGNOR TO
GENERAL ELECTRIC COMPANY, A CORPORATION OF NEW YORK.

STARTING-RHEOSTAT FOR ELECTRIC MOTORS.

SPECIFICATION forming part of Letters Patent No. 690,448, dated January 7, 1902.

Application filed July 15, 1901. Serial No. 68,831. (No model.)

To all whom it may concern:

Be it known that I, FREDERICK MACKINTOSH, a citizen of the United States, residing at Schenectady, county of Schenectady, State 5 of New York, have invented certain new and useful Improvements in Starting-Rheostats for Electric Motors, (Case No. 2,124,) of which the following is a specification.

This invention relates to devices for controlling electric motors, and can be used with any electrically-driven tool where it is desirable to vary the voltage greatly and with fine graduations and suppress sparking at the brush or contact conveying current to a moving part of the motor.

The invention is especially valuable in connection with the electric pluggers or mallets used by dentists. The contacts or "vibrators" in these tools are necessarily small and delicate and are quickly burned up if a high voltage is used without some means to prevent the spark when the circuit is broken at each blow of the plunger. Moreover, it is very desirable to be able to regulate the force 25 of the blow through a considerable range.

In the following portion of this specification I shall describe my invention in its use with a dental plunger.

It consists of a rheostat divided into two or 30 more portions connected in series, with means for independently varying one or more of said portions and means for shunting the motor through the variable section of one of said portions. The spark at the motor-contacts is 35 killed by this shunt.

In the accompanying drawings, Figure 1 is a perspective front view of a rheostat embodying my invention. Fig. 2 is a diagram of the circuits.

40 The several switches and binding-posts are mounted on the usual slab A, of slate or other insulation, behind which is the customary case B, of perforated metal, to contain the resistance-coils. The line-terminals are connected with the two binding-posts C C' and the mallet or plunger terminals with the two binding-posts D D'. The posts C' and D' are connected by wire 1. A wire 2 leads from the post C to a resistance E, whose coils are 45 connected with a plurality of contact-points e. A switch-arm F makes contact with any one of said points, and thereby varies the number of coils in circuit. The switch-arm is connected by a wire 3 with one end of a sec-

ond variable resistance E', preferably through 55 a fixed resistance E''. The coils of the resistance E' are connected with a plurality of contact-points e', and a wire 4 connects the other end of said resistance with the binding-post C'. A switch-arm G makes contact with 60 the points e' and is connected by wire 5 with the binding-post D. By varying the resistance E the normal voltage supplied to the plunger can be set at any one of several given values. By moving the switch-arm G the 65 voltage can be raised from zero to the limit set by the switch-arm F, the current dividing between the plunger and that portion of the resistance E' between the switch-arm G and the wire 4, said portion being in shunt to the 70 plunger. There is thus always a closed circuit across the line-terminals, so that the vibrator of the plunger will operate without sparking.

What I claim as new, and desire to secure 75 by Letters Patent of the United States, is—

1. In a starting-rheostat, a resistance connected across the line and divided into two or more portions one of which is variable, and motor-terminals one of which is connected 80 with one side of the line, and the other with means for connecting it with any point on another portion of said resistance.

2. In a starting-rheostat, a resistance connected across the line and divided into two 85 or more portions, a switch-arm for varying one of said portions, and means for connecting a motor in shunt to a variable section of another portion.

3. In a starting-rheostat, a resistance connected across the line and divided into two 90 or more portions, a switch-arm for varying one of said portions, and motor-terminals one of which is connected with one side of the line, and the other with a switch-arm making 95 varying contact with another portion of said resistance.

4. In a starting-rheostat, means for varying the total voltage supplied to a motor, and means for varying said voltage and at the 100 same time varying the resistance of a shunt around said motor.

In witness whereof I have hereunto set my hand this 13th day of July, 1901.

FREDERICK MACKINTOSH.
